UNITED STATES PATENT OFFICE.

THOMAS E. MOLDON, OF TORONTO, ONTARIO, CANADA.

COIL-WINDING MACHINE.

Application filed July 11, 1923. Serial No. 650,965.

To all whom it may concern:

Be it known that I, THOMAS E. MOLDON, citizen of the Dominion of Canada, and a resident of Toronto, county of York, and Province of Ontario, Canada, have invented a new and useful Improvement in Coil-Winding Machines, of which the following is a specification.

My invention relates to machines for winding strands of material such as wire, thread, ribbon or filaments, into coils, helices or bobbins, and pertains specifically to machines for winding copper wire into electrical coils or helices for use in electrical apparatus.

The object of my invention comprises producing a machine in which the transverse or lateral feed for the material being wound may be altered without necessitating changes in gearing or cams, in order that the machine may be quickly and easily adapted to wind various sizes of wire or other material.

I accomplish these and other desirable features which will hereinafter be pointed out and discussed, by means of the novel arrangement illustrated in the drawings and described in the accompanying specification.

In the drawings which accompany and form a part of this specification, and in which like reference numerals designate corresponding parts throughout;

Fig. 1 is a plan view of a simplified form of winding mechanism incorporating my novel device.

Fig. 2 is a front elevation of the same.

Fig. 3 is a sectional view taken on the line 3—3 of Fig. 2.

Fig. 4 is a partially sectioned enlarged view of a detail of the reversing mechanism.

Referring now specially to Figs. 1 and 2, I have chosen to illustrate my novel device as incorporated in an extremely simple form of winding machine, as my invention is independent of the particular form of driving or reversing mechanism, and may be used in conjunction with many various forms of driving and reversing mechanisms. Therefore, while it is necessary to enter into some detail in describing even the simple reversing mechanism shown, it is understood that no claim is made to that part of the device.

In Fig. 1 the base 1, preferably of cast iron, is provided with bearings 2 and 3 adapted to carry the shaft 6 which is provided with a driving pulley 5, the spur gear 7 and a simple form of clutch 60, which is likewise adapted to receive and support the mandrel 61, which in turn carries the spool or bobbin 12 upon which it is desired to wind the wire or strand. An auxiliary base member 13 is provided and secured to the major base 1, and serves as a bearing for a driven shaft 9, one extremity of which is carried by the bearing member 3. The shaft 9 carries a spur gear 8 meshing with spur gear 7 and united to a bevel gear 19. The bevel gear 19 turns with spur gear 8 and both turn loosely on the shaft 9. A bevel gear 45 is pivoted in a support 50 and meshes with bevel gear 19 and likewise with bevel gear 20 carried by, but adapted to rotate loosely on shaft 9. Between the bevel gears 19 and 20 there is provided as shown in Fig. 4, a double cone clutch member 48, which is splined to the shaft and is free to slide thereon, as shown in Fig. 4. A split ring 60 is carried in a channel in the member 48 and is provided with a pin 44 extending through a slot 24 in the reversing lever 26. One extremity of the lever 26 is pivoted by means of the pin 25 in the bearing member 50, the other extremity of which is provided with a pin 23 encircled by a spring member 22, the other extremity of which is articulated with a pin 21 carried by a shaft 14 for a purpose which will hereinafter be described.

A follow nut 32 is carried by the threaded portion of the shaft 9, and as shaft 9 is driven, traverses the shaft from left to right or from right to left dependent upon the direction of rotation of the shaft. As shown in Fig. 3, this follow nut is given a shape such as to encircle and slide on shaft 14, between adjustable stops 17 and 15. Collars 18 and 16 are provided on shaft 14 to limit the lateral motion of the shaft. It will be obvious that as the follow nut 32 is moved either to the right or left during the operation of the machine, at each extreme of its motion, it will engage with stop 17 or 15 to propel shaft 14 to the right or left, and these stops are set in accordance with

- the width of the winding desired. The lateral motion of the shaft 14 causes a reversal of the direction of the motion of the follow nut 32, because as pin 21 is carried to the right or left of the center line passing through pin 23, and the pivot point 25 of the lever 26, the lever is moved to the right or left as the case may be, and such motion results in bringing the edges of slot 24
- 10 against pin 44 with a sharp impact to de-clutch the clutch cone 48 from one of the bevel gears and causes it to engage the other of the pair to cause a reversal of rotation of shaft 9, and hence a reversal of the lateral motion of follow nut 32.

The guide rod 10 is carried in bearings provided in the auxiliary base 13 and is adapted to move laterally therein. The guide rod 10 carries at one extremity a wire or filament guide 11 composed of a pair of deep grooved pulleys maintained in a support which is securely attached to the rod 10.

A supporting rod 27 is securely attached to a boss formed on the auxiliary base 13, and is maintained with its longitudinal axis at right angles to the longitudinal axes of the shafts 9 and 14, and of the guide rod 10. The rod 27 carries a bearing support 28 adjustably secured to the rod near its free extremity by means of the clamping nut 52. A sleeve bearing 55 is mounted on the bearing support 28 and is retained in a rotatable manner by the pointed set screw 51 as shown in Fig. 3. The sleeve 55 serves to slidably support one extremity of a pantograph rod 29, the other extremity of which is pivotally mounted by means of the block 71, and the shouldered screw 70 on the follow nut 32 as indicated in Fig. 3.

40 A slotted adjustment member 30 is secured by means of a set screw 53 to the guide rod 10. The attachment of the member 30 with the guide rod is preferably made when the follow nut 32 is at the midpoint of its travel on the shaft 9. The guide rod 10 is then moved so that the wire guide 11 is in line with the mid point of the coil or bobbin to be wound, and the slotted member 30 is then clamped to the guide rod 10 at a point 45 midway between the supports for the rod in the auxiliary base member 13.

A clamping nut, the stem 48 of which is rigidly united with a sleeve 47, which is adapted to slide on the pantograph rod 29, 55 is provided with a collar 41 and a knurled thumb screw 31, by means of which the position of the collar 47 along the pantograph rod may be varied and the pivot point of the rod 29 with the slotted member 30 predetermined and fixed as indicated by the graduations shown on the member 30 in Fig. 1.

It will be observed from the foregoing that as the follow nut 32 traverses the threaded shaft 9 in the operation of the device, the pantograph rod 29 will be swung

about its pivot point 55 with the support rod 27, and that further the guide rod 10 will be moved a distance to the right or left, which is dependent upon the position of the clamping nut 48 with regard to the slotted member 30. It being readily understood that as the clamping nut 48 is moved upward in the slotted member 30 as viewed in Fig. 1 the travel of the guide rod 10 carrying the wire guide 11 will be shortened for a given length 70 of travel of the follow nut 32, and therefore the travel of the wire guide with relation to the spool being wound, is shortened for a given number of revolutions of the spool; conversely, as the clamping nut 48 is moved downward in the slotted member 30 as viewed in Fig. 1, the wire guide 11 will be moved through a greater distance for the same number of revolutions of the bobbin being wound. Obviously, this permits an extremely close adjustment of the lateral feed for the device, and enables various sizes of wire to be wound by simply changing the position of the clamping nut 48 with respect to the slotted member 30. It is obvious, further, that if the slotted member 30 be calibrated for various sizes of wire, that it may be graduated so that the machine may be quickly, simply and easily adjusted to wind various sizes of wires or filaments. It will be obvious further, that the stops 17 and 15 upon the reversing shaft 14, may be positioned to wind various width of coils. It is further obvious from this discussion, that my invention, which relates to the mechanism for quickly and easily adjusting the machine to wind various diameters of filament, may be incorporated to function with machines employing many different types of reversing or driving mechanisms. It will be 105 further obvious that the length of the slotted member may be increased to give the machine a wide latitude of adjustment.

While I have illustrated and described one simple embodiment of my machine, it should be clearly understood that I may vary the details thereof, without departing from the spirit or narrowing the scope of my invention.

Having thus completely described my invention, what I claim as new and desire to secure by United States Letters Patent is as follows:—

1. A coil winding mechanism comprising, a bobbin, means for rotating said bobbin, a filament guiding means adapted to be moved laterally with respect to said bobbin, a screw for moving said filament guiding means, a rod adapted to be rotated about an adjustable supporting pivot by means of said screw, and means for articulating said guiding means with said rod at selected points along the longitudinal axis thereof to increase or decrease the pitch of the winding.
2. A coil winding mechanism comprising,

a bobbin, means for rotating said bobbin, a filament guiding means adapted to be moved laterally with respect to said bobbin, a screw driven by said bobbin rotating means, and adapted to move said filament guide, a rod supported in an adjustable pivot and adapted to be rotated about said pivot by means of said screw, means for selectively articulating said guiding means with said rod to increase or decrease the pitch of the filament winding on said bobbin and means for reversing the direction of rotation of said driven screw. 10

THOMAS E. MOLDON.
